FLAT SHAFT CONTROL DEVICE

Harry W. Rubinstein, Milwaukee, Wis., assignor
to Globe-Union, Inc., Milwaukee, Wis., a corpora-
tion of Delaware

Application April 3, 1939, Serial No. 265,787

11 Claims. (Cl. 64—4)

This invention relates to an improvement in a control or operating device of the type commonly used on electrical apparatus or appliances as for example, on a radio receiver for controlling the volume of the reception or reproduction or for similar purposes.

In the case of a volume control of a radio receiver it is customary to constitute the operating shaft for the movable contact or the variable resistance embodied in such a control of circular form or round stock, the shaft extending from the movable contact inside the casing of the control through a bushing combined with the casing to some more or less remote point, such as the panel of the radio, at which point it is interconnected with an operating knob.

The resort to the use of shafts of round stock has been considered necessary in order to provide a structure adapted to be conveniently supported for rotation in the bushing of the volume control, although it has the distinct disadvantage of requiring the use of a considerable amount of metal and the necessity of more or less expensive machining operations.

One of the principal objects of the present invention is to provide a structure of this character which makes it practical and convenient and satisfactory to employ a shaft of flat wire or equivalent flat metal stock, one which may be punched or cut from a sheet or strip of metal very quickly and very readily and very inexpensively so that in the final structure there is a substantial saving in cost of production as well as in the amount of material or metal used. Not only is this advantage realized but the structural elements which combine the flat stock shaft with the volume control are also punch press parts. The necessity of manufacturing elements on the screw machine or the resort to similarly expensive and time consuming operations are entirely avoided. Nevertheless in the assembly the flat wire shaft is firmly and effectively supported for rotative adjustment and will not wobble or spring or vibrate or be otherwise disadvantageous when employed on a radio receiver.

Another object is to provide a bushing and control mounting arrangement adapted for use with various types of volume controls and possessed of the distinct advantage of simplifying, compacting and rendering less expensive the cost of production of such devices and yet rendering the device susceptible of ready production and of easy and ready and practical assembly to the chassis of a radio receiver.

Other objects and advantages reside in certain novel features of the construction, arrangement, and combination of parts which will be herein-after more fully described and particularly pointed out in the appended claims, reference being

had to the accompanying drawings forming a part of this specification, and in which:

Figure 1 is a view partly in side elevation and partly in central vertical cross section showing a control device embodying the present invention;

Figure 2 is a group view in perspective showing the shaft and its mounting sleeve prior to assembly with the bushing of a volume control;

Figure 3 is a view in end elevation looking toward the right hand end of Figure 1 but showing the cover of the control removed and illustrating parts broken away to show the metal of the volume control;

Figure 4 is a fragmentary view partly in central vertical section and partly in side elevation showing a modified form of the invention;

Figure 5 is a view similar to Figure 4 but showing still another form of the invention;

Figure 6 is a view similar to Figures 3 and 4 but illustrating the fourth modification of the invention;

Figure 7 is a view similar to Figure 6 but showing still another form of the invention;

Figure 8 is a view in end elevation looking toward the left hand end of Figure 9, parts being broken away, the parts being shown in section for the sake of illustration;

Figure 9 is a view similar to Figure 6 but showing still another form of the invention;

Figure 10 is a view illustrating how the structure may be adapted for use with extension shafts;

Figure 11 is a fragmentary view in top plan of the central portion of the structure shown in Figure 10.

Figure 12 is a fragmentary view partly in side elevation and partly in central vertical cross section showing still another embodiment of the invention,

Figure 13 is a fragmentary group view in perspective of the complementary sections of a shaft in another embodiment of the invention; and

Figure 14 is a view showing the shaft structure illustrated in Figure 13 assembled and combined with an adjustable resistor.

Referring to the drawings and more particularly to Figures 1 to 3, it will be seen that in the embodiment of the invention therein described the volume control is designated generally at 10 and is of the type having a casing or housing 11 of insulating material which is equipped with a metal cover 12 having extensions 13 terminating in tabs 14 which are bent around or clinched over to secure the cover in place. The structure of the volume control per se forms no part of the present invention but it may be well to point out that it usually includes a resistance element 14' in the form of a carbonaceous or conductive coated strip of paper of similar flexible material across which a movable contact 15 is adjusted.

The rotation of the movable contact is effected by means of an operating shaft designated generally at 16, which extends from the volume control through the front panel 17 of the radio receiver, the projecting end of the shaft having a knob 18 suitably attached thereto so as to facilitate turning of the operating or control shaft. In the present instance the volume control has a fixed bushing 20 combined therewith in a special way. This bushing is made up of a piece of cylindrical sheet metal tubing, the inner end of which extends through an opening in the back wall of the casing and is flanged or spun over as indicated at 21. A mounting plate 22 is provided and has a central opening which fits over the bushing 20, the mounting plate being disposed flush up against the adjacent end wall of the housing 11. To secure the mounting plate 22 to the housing and also fasten the bushing 20 in position, the bushing is provided with a corrugation 23 which engages the mounting plate 22 around the margin of its opening so that when the flange 21 is formed or spun during the assembly of the parts it, together with the corrugation 23, will clamp the mounting plate firmly to the housing as well as secure the bushing in position. In use, the bushing 20 is inserted through an opening in a supporting member 24 which may be a part of the chassis of the radio receiver and tabs or lugs 25 formed integral with the mounting plate 22 extend through slots in this supporting member and are bent or clinched over as shown in Figure 1. An insulating washer or layer 24' may be interposed between the mounting plate 22 and the chassis or supporting member 24.

One of the important features of the present invention resides in the use of an operating shaft 16 of flat stock and in the means provided for rotatably supporting such a shaft. In the present embodiment of the invention this is accomplished by providing a mounting sleeve 26 of cylindrical form and designed to be a snug rotating fit in the bushing 20. The inner end of the mounting sleeve is provided with an end wall 27 in which a diametrically extending slot 28 is formed. The outer end of the mounting sleeve is provided with an outwardly extending flange 29 provided at diametrically opposite points with notches 30. When the mounting sleeve is assembled with its bushing 20 its flange 29 rides on the outer end of the bushing 20.

The inner end of the shaft 16 is provided with steps or reduced portions 31 and 32 and there are shoulders 33 presented at the juncture of the reduced portions or step 31 and the main portion of the shaft 16. In the assembly these shoulders 33 positively interfit with the notches 30 of the flange 29. The edges 31a of the step 31 engage opposed portions of the inner peripheral wall of the mounting sleeve and the inner end portion of the step 31 is a snug fit in the diametric slot 28 of the end wall 27. The step 32 extends through a slot provided therefor in the carrier 15' for the movable contact 15 and is upset or riveted over into secure engagement therewith as indicated at 32'. Interfitting the shaft and mounting sleeve in this way precludes any wobbling or transverse displacement of the flat shaft. The engagement of the shoulders 33 and the notches 30 also prevents axial shifting of the shaft 16 to the right, as viewed in Figure 1. The connection between the inner end of the shaft 16 and the contact carrier 15' prevents

axial shifting of the shaft 16 in the opposite direction.

The shaft is thus supported in a steady and secure fashion, though for free rotation, notwithstanding that it is made of flat stock or flat wire 5 and is supported by cylindrical parts which are interfitting for turning movement with respect to each other.

The shaft 16 with its steps 31 and 32, the eyelet 26 with its end wall 27 and slot 28 and also with 10 its flange 29 and notches 30 are employed in all embodiments of the invention and are related and combined in just the manner above described.

The several embodiments of the invention differ from each other in the construction of, or in 15 the manner of combining the fixed bushing with, the volume control, or in the manner of supporting the assembly on the chassis of the radio receiver. In one instance, there is also illustrated 20 the capability of the structure for use with extension shafts.

In the structure shown in Figure 4 the fixed bushing is made up of an eyelet 33' having its inner end spun or flanged over the margin of the opening in the adjacent end wall of the 25 housing and having its outer end spun or flanged over a collar 34 fitted over the projecting portion of the bushing 33' and having a base flange 35 flushly engaging the mounting plate. In other respects the structure of the embodiment shown 30 in Figure 4 is similar to that shown in Figure 1.

Figure 5 illustrates that the fixed bushing designated at 40 may be moulded as one piece with the insulating housing of the volume control, the bushing receiving the eyelet 26 which 35 coacts therewith and with the shaft 16 as before. With such a construction securing tabs 41, integral with the extensions 42 of the metal cover 43 of the volume control 10, coact with the chassis 24 of the radio receiver to secure the assembly 40 in position.

In the structure shown in Figure 6 the housing of the volume control is provided with a machined fixed bushing 45 which coacts with the nut 46 to secure the assembly in position. The 45 mounting sleeve 26 is combined with the fixed bushing 45 and with its shaft 16 as before.

The form of the invention shown in Figure 7 is very similar to that shown in Figure 4 in that it employs an eyelet 33 for its fixed bushing. It 50 differs from the form shown in Figure 4 in that the collar 34 corresponding to collar 34 is formed as an integral part of the mounting plate 22 rather than as a separate piece.

In the form of the invention shown in Figures 55 8 and 9 the fixed bushing designated at 50 is spun out as an integral portion of the casing 51 of the volume control device and extends through the opening in the chassis of the radio receiver. Tabs 52 struck from the metal casing of the 60 volume control are clinched over slots in the chassis to support the assembly in position.

Figures 10 and 11 illustrate any of the foregoing structures may readily be combined with an extension shaft 53 of circular form. This is 65 accomplished by providing the shaft 53 with a slot 55 in its end and an annular groove 56 surrounding the slot. The shaft 16 is cut off and is provided with notches 57 designed to be aligned with the grooves 56 so that when the parts are interfitting a snap ring 58 may be employed to releasably secure them assembled. Preferably 70 also the extreme outer end of the shaft 16 is formed with a reduced extension 16' fitted or piloted in a socket 59 in the shaft 53. 75

In the form of the invention shown in Figure 12 the volume control 10 is shown as being of the same general type illustrated in Figures 1 to 3, although the metal cover is not shown, but in practice is supplied and functions as in Figure 1 to secure the insulating casing 11 of the control to the mounting plate 22 as before, and tabs 25 on the mounting plate fasten the assembly to the chassis 24. The fixed bushing designated in Figure 12 at 62, is formed integral with the mounting plate. In this form of the invention instead of a single mounting sleeve or rotating bushing, two mounting sleeves or rotating bushings designated at 60 and 61 are provided. These mounting sleeves are fitted over the steps of the end of the shaft 16 and are a close working rotative fit in the fixed bushing 62. The mounting sleeve 60 has an outwardly directed angular flange 63 at its outer end which is in rotative engagement with the outer end of the fixed bushing 62 and which abuts a shoulder 33 on the shaft 16 as before. However, the notches 30 are omitted as they are not necessary when two mounting sleeves are employed.

25. The inner end of the mounting sleeve 60 is formed with an integral end wall which has a diametrical slot through which the associated portion of the shaft 16 extends and in which such portion of the shaft is snugly fitted. The inner mounting sleeve 61 has its outer end formed with an integral end wall which has a diametrical slot receiving the step at the extreme inner end of the shaft 16. The inner end of this mounting sleeve 61 has the portions thereof at the ends of its diametrical slot abutting a shoulder formed on the shaft 16 by the adjacent steps thereof. The extreme inner end of the shaft 16 is connected to the rotatable members of the volume control.

40. By having two bushings or mounting sleeves it is convenient and economical to closely control the diameter thereof, so that they are a snug working rotative fit in their fixed bushings and it is not necessary to accurately control their 45 length. This facilitates and renders much more economical the production of the eyelets.

Some of the advantages of the invention may be achieved without the use of the mounting sleeves or bushings by specially constructing the 50 flat stock shaft and providing it in two complementary sections. For example, as illustrated in Figures 13 and 14, a short shaft section of flat stock designated at 70 may be provided. This short section has its one end reduced as at 10' and upset or otherwise suitably secured to the 55 adjustable member 71 of the adjustable resistor 12. The housing of this resistor may be supported in any suitable way on the chassis or supporting member 13 and usually it has some form 60 of fixed bushing 74 extending through an opening in the chassis and secured in position in some suitable way as for instance, by means of a nut 75. The short shaft section 70 is provided 65 at its outer end with a longitudinally extending slot 76 and also has spaced notches 77 in its opposite edges, the notches being transversely aligned. Cooperable with the short shaft section 70 is an elongated shaft section 80 also of flat 70 stock and of any suitable length. To one end of the shaft section 80 the knob (not shown) is attached. The end of the shaft section 80 which is designed to cooperate with the short shaft section 70 also has a central longitudinally extending slot 81 and notches 82 in its opposite edges.

Both of the shaft sections and their edges form with a radius struck on the arc corresponding to that of the fixed bushing in which they are fitted in the assembly. The shaft sections are assembled in the manner illustrated in Figure 14, that is, with their slots interfitting and the portions of the sections on the opposite sides of the slots overlapping unslotted portions of the shaft sections. When assembled the shaft sections are disposed at right angles to each other and their notches 77 and 82 are aligned to receive snap rings 83 and 84 which are employed to maintain them assembled and also to maintain the shaft assembly against axial movement in its position.

15. While I have shown and described several constructions in which the invention may be advantageously embodied, it is to be understood that the constructions shown have been selected merely for the purpose of illustration or example 20 and that various changes in the size, shape and arrangement of the parts may be made without departing from the spirit of the invention or the scope of the subjoined claims.

The invention claimed is:

1. In combination with an electrical control device including a casing and a rotatable control element in said casing, a mounting bushing secured to and projecting from the casing, an operating shaft for said control element, said 30 shaft being of flat stock, and a mounting sleeve having a rotative fit in the bushing and having its inner end closed and provided with a diametrical slot, the outer end of said mounting sleeve having an outwardly directed annular 35 flange in rotative engagement with the outer end of the bushing and provided with diametrically opposite notches, said shaft having a stepped portion extending through said mounting sleeve and into the casing, the step disposed in said 40 mounting sleeve having its edges engaged with the inner peripheral wall of said mounting sleeve and fitted snugly in said slot, the juncture of said step and the main portion of the shaft presenting shoulders interfitting with said notches and acting conjointly with said interfitting step and 45 slot and with the engagement of said edges with the inner peripheral wall of said mounting sleeve to secure the shaft against any transverse displacement with respect to said mounting sleeve 50 or its bushing, the engagement of the shoulders with the notches and the engagement of said flange with the outer end of the bushing also preventing axial shifting of the shaft in one direction, the extreme inner end of the shaft having another step interfitting with and secured to 55 said rotatable control element to provide a driving connection between it and the shaft and to prevent axial shifting movement of the shaft in the other direction.

2. In combination with a device having a casing, a cylindrical bushing secured to and projecting from the casing, a cylindrical mounting sleeve rotatively fitted in the bushing and having an end wall at its inner end provided with a diametrical slot, the outer end of said mounting sleeve being provided with an outwardly directed angular flange riding on the outer end of the bushing, said flange having diametrically opposite notches, and a shaft of flat stock having a reduced end extending through said mounting 70 sleeve and through the slot in the inner end wall thereof, and being of such width that its edges snugly engage the inner periphery of said mounting sleeve and the end walls of said slot; the shoulders at the juncture of said reduced portion 75

and the main portion of the shaft being interfitted with said notches.

3. In combination with a device having a casing, a cylindrical bushing secured to and projecting from the casing, a cylindrical mounting sleeve rotatively fitted in the bushing and having an end wall at its inner end provided with a diametric slot, the outer end of said mounting sleeve being provided with an outwardly directed angular flange riding on the outer end of the bushing, said flange having diametrically opposite notches, and a shaft of flat stock having a reduced end extending through said mounting sleeve and through the slot in the inner end wall thereof, and being of such width that its edges snugly engage the inner periphery of said mounting sleeve and the end walls of said slot, the shoulders at the juncture of said reduced portion and the main portion of the shaft being interfitted with said notches, said interfitting of the shoulders with said notches preventing axial movement of the shaft in one direction, and means cooperable with the inner end of the shaft and preventing axial movement thereof in an opposite direction.

4. In combination with an electrical control device having a casing containing a rotatable control element, a bushing secured to the casing and projecting therefrom, a mounting sleeve rotatably fitted in said bushing and having one end provided with a slotted end wall and its other end open and formed with an outwardly extending flange riding on an end of the bushing, said flange being provided with notches in opposed portions thereof, and an operating shaft of flat stock having a portion interfitting with said notches and having edges of another portion in snug engagement with the inner peripheral wall of said mounting sleeve and also having a portion snugly interfitted with said slot, the inner end of the shaft being interconnected with said control element and secured thereto.

5. A device of the character described comprising a casing having a cylindrical bushing projecting therefrom and fixed thereto, a rotatable bushing supported in the fixed bushing and having a flange at its outer end riding on the outer end of the fixed bushing and provided with notches, the inner end of the rotating bushing having an end wall provided with a transverse slot aligned with the notches of the flange, and an operating shaft of flat wire stock having a portion interfitted with the notches and having a smaller portion engaged with the inner periphery of the rotative bushing and snugly fitted in the slot in the inner end wall thereof.

6. A control device of the character described including a fixed bushing, a mounting sleeve rotatably fitted in said bushing and having one end provided with a slotted end wall and its other end open and formed with an outwardly extending flange riding on the outer end of the bushing, said flange having notches in opposed portions thereof, and an operating shaft of flat stock having a portion interfitted with said notches and having edges of another portion in snug engagement with opposed portions of the inner peripheral wall of said mounting sleeve and also snugly engaged with said slotted end wall.

7. In combination with an electrical control device including a casing and a rotatable control element in said casing, a mounting bushing secured to the casing and projecting therefrom, an operating shaft for said control element, said

shaft being of flat stock, and a mounting sleeve having a rotative fit in the bushing and having its inner end closed and provided with a diametrical slot, the outer end of said mounting sleeve having an outwardly directed annular flange having rotative engagement with the outer end of the bushing and being provided with diametrically opposite notches, said shaft having a stepped portion extending through said mounting sleeve and into the casing, the step disposed in said mounting sleeve having its edges engaging the inner peripheral wall of said mounting sleeve and snugly fitted in said slot, the juncture of said step and the main portion of the shaft presenting shoulders interfitted with said notches and acting conjointly with said interfitted step and slot and with the engagement of the edges with the inner peripheral wall of said mounting sleeve to secure the shaft against any transverse displacement with respect to said mounting sleeve or its bushing, the inner end of the shaft having another step being secured to said rotatable control element to provide a driving connection between it and the shaft.

8. A control device of the character described comprising a casing having a bushing fixedly connected thereto and projecting therefrom, a mounting sleeve rotatably fitted in the bushing and having an end wall at its inner end provided with a slot and also having an outwardly directed annular flange at its outer end provided with notches, an operating shaft of flat stock positively connected with the notches of the flange and the slot of the inner end wall, and a connection between the inner end of the shaft and the element to be controlled.

9. A control device of the character described comprising a casing having a bushing fixedly connected thereto and projecting therefrom, a mounting sleeve rotatably fitted in the bushing and having an end wall at its inner end provided with a slot and also having an outwardly directed annular flange at its outer end provided with notches, an operating shaft of flat stock positively connected with the notches of the flange and the slot of the inner end wall, a connection between the inner end of the shaft and the element to be controlled, and means cooperable with the bushing to support the assembly on a fixed support.

10. A control device of the character described comprising a casing having a fixed bushing, a hollow cylindrical mounting sleeve rotatably supported in said bushing, said mounting sleeve being provided with an end wall, a diametrical slot formed in said wall, and an operating shaft of flat stock extending within said sleeve, portions of the edges of said shaft being engaged with the inner peripheral wall of said sleeve, the sides of said shaft being engaged with said slot.

11. A control device of the character described comprising a casing having a fixed bushing, a hollow cylindrical mounting sleeve rotatably supported in said bushing, said sleeve having an outwardly directed annular flange having rotative engagement with the end of said bushing, and an operating shaft of flat stock extending within said sleeve and having portions of its edges in engagement with the inner peripheral wall of said sleeve, there being interlocking means between said flange and said shaft to prevent relative rotative movement therebetween.
